COMBINED BOTTLE AND CAP THEREFOR

Dutro Blocksom, Jr., Cincinnati, Ohio, assignor to The Procter & Gamble Company, Cincinnati, Ohio

Filed Sept. 11, 1972, Ser. No. 287,741

Term of patent 14 years

Int. Cl. D9—01

U.S. Cl. D9—147

FIG. 1 is an elevational view of a combined bottle and cap therefor showing my new design, the opposite side being the same in appearance as the side shown;

FIG. 2 is an elevational view with the cap removed;

FIG. 3 is a top plan view with the cap in place; and

FIG. 4 is an elevational view of the cap partially in section.

I claim:

The ornamental design for a combined bottle and cap therefor, as shown and described.
